(74) Attorney, Agent, or Firm — Andrew F. Young, ESQ.;
NOTLE LACKENBACH SIEGEL(57) **CLAIM**

The ornamental design for a robot, as shown and described.

DESCRIPTION

FIG. 1 is a front, left, top perspective view of a robot, showing my new design.

FIG. 2 is a rear, right, top perspective view thereof.

FIG. 3 is a front view thereof.

FIG. 4 is a rear view thereof.

FIG. 5 is a right side elevation view thereof.

FIG. 6 is a left side elevation view thereof.

FIG. 7 is a top plan view thereof; and,

FIG. 8 is a bottom view thereof.

The dash-dot-dash lines demarcate the boundary of the claim beyond which no claim is made. The dash-dash disclaimed linking represents environmental features that form no part of the claimed design. No claim is made to portions that are not shown.
